UNITED STATES PATENT OFFICE.

GEORGE F. KIRCHHOFF, OF CHICAGO, ILLINOIS, ASSIGNEE, BY MESNE ASSIGNMENTS,
TO MAX HARRIS, OF PITTSBURGH, PENNSYLVANIA.

AUTOMATIC SWITCH FOR FLASHERS, &c.

1,101,494.

Specification of Letters Patent. Patented June 23, 1914.

Application filed May 10, 1911. Serial No. 628,968.

To all whom it may concern:

Be it known that I, GEORGE F. KIRCHHOFF, a citizen of the United States, and a resident of Chicago, in the county of Cook and State of Illinois, have invented certain new and useful Improvements in Automatic Switches for Flashers, &c., of which the following is a full, clear, and exact specification.

10 My invention is concerned with automatic electric switch mechanism, designed primarily for "flashers," as they are called, but which may be employed for other purposes, and consists essentially of a pair of magnets 15 with a pair of associated switches and a pair of associated dash pots or similar retarding devices, all combined so that they will operate alternately to open and close a single work circuit or to open one work circuit and simultaneously close another and vice versa.

To this end my invention consists in a certain novel structure and arrangement of elements which will be described at length in 25 the body of the specification and the novel combinations particularly pointed out in the claims.

To illustrate my invention, I annex hereto two sheets of drawings in which the same reference characters are used to designate identical parts in all the figures, of which— Figure 1 is a front elevation of the switch mechanism removed from the oil holding receptacle in which it is ordinarily immersed; Fig. 2 is a similar view in side elevation of the same mechanism; Fig. 3 is a front elevation in section on the line A—A of Fig. 2; Fig. 4 is a diagrammatic view showing the circuits; and Fig. 5 is a similar 40 view, showing one work circuit instead of the two shown in Fig. 4.

I have designed my novel switch so that it is especially adapted to operate in an oil filled tank, in which it will be understood 45 to be immersed, although I have not illustrated the tank.

The various elements are located on an insulating slab 10, which is provided with the five binding posts 11, 12, 13, 14 and 15, 50 at its upper end and the wire from the positive side is connected to the post 11 and from the negative side to the post 12. Where the switch is used as a flasher for the two sets of lamps, as indicated in Fig. 4, the post 14 will be connected to the positive side 55

of one set of lamps 16, while the post 15 will be connected to the positive side of another set of lamps 17, and a common return wire 18 may be connected to the negative side of both sets of lamps and to the post 13, which 60 in that case will be connected to the post 12 by the wire 19. The binding posts 20 and 21 are electrically connected to the switch contacts 22 and 23 and where it is connected up for two circuits, as indicated in Fig. 4, 65 there will be two other binding posts 24 and 25 connected with the switch contacts 26 and 27. The binding post 11 is connected by the wire 28 with the post 20, which in turn is connected by the wire 29 with the 70 binding post 24. The binding post 21 is connected by the wire 30 with the binding post 14, while the binding post 25 is connected by the wire 31 with the binding post 15. A switch having two blades 32 and 33 75 is pivotally mounted upon the standards 34 and 35, and the upper ends of the blades 32 and 33 are adapted to engage the contacts 22 and 23 while the lower ends of the blades are adapted to engage the contacts 80 26 and 27. The two blades are electrically connected in any desired manner as by the three spacing rods 36, 37 and 38, and it will be readily apparent that when the upper end switch blades 32 and 33 are in engagement 85 with the contacts 22 and 23, the circuit will be closed from the positive main through the contact 22, switch contact 23, wire 30, contact 14, the lamps 16, return wire 18, contact 13, wire 19, and contact 12 to the 90 negative main. When the switch is in the other position, as indicated in the dotted lines in Fig. 2, the circuit will be closed through the contacts 24 and 25, wire 31, contact 15, lamps 17 and return wire 18 as 95 before.

To control the automatic operation of this switch where the device is used as a flasher, so that first one circuit will be closed for a time and then the other, I employ the following device: Suitably supported from the base piece 10 by the lugs 29^a and 40^a are a pair of solenoid magnets 39 and 40, which are shown in axial alinement and preferably have the single supporting tube 41 shown 100 105 with the three flanges forming, as it were, two spools. The main core 42 of the lower solenoid is preferably a heavy metal rod and carries on the lower end thereof the piston 43, adapted to coöperate with the dash pot 110

44. The lower end of the lever 50 is longer than the upper end so that the lever rests on the downward movement of the plunger 46, and may be suddenly received as such to hold the lever 46 by gravity and give a greater impetus to the action of the two arms 44 and 45 of impacting material as will be explained later. 45. The arms 44 and 45 will impact the arms 47 and 48 and swing the switch blades 21 and 22 from the full line position of Fig. 2 to the vertical line position of Fig. 3. 46. The lever 50, during its downward movement, will impact the arms 44 and 45 against the surfaces 49 and 50 on the rear side of the impact arms, swinging the switch blades 21 and 22 from the full line position of Fig. 2 to the vertical line position. 47. In order to return the plunger 46, during somewhat lighter impact, to the upper end of the dash pot 45, it is necessary to open the plunger 46, which is in contact with the switch blades 21 and 22, so that the plunger 46 may be caused to impact the switch blades 21 and 22. 48. The upper switch 20 has a switch arm 51 which fits very loosely in the switch 20 so that the oil can pass without hindrance to the plunger 46 so as not to interfere with its movement in the dash. 49. The lower solenoid 52 has an auxiliary plunger 53 which is directly connected to the plunger 46 by the rod 54 so as to move with said plunger. 50. Considering that in some cases it will be desired to put the solenoid 52 in there magnetized and that it acts on the arm 51 so that it can and likewise unimpededly pass when the core of the solenoid 52 is energized, it is apparent, the solenoid 52 is magnetized so that its core 53 is drawn up into the solenoid 52 so that it is deformed and the dash pot 45 held down by its connection with the movable arm 51 of the solenoid 52, it will be understood that in all cases as the arm 51 of the lower movement of the core of plunger 46, it impacts the auxiliary core 53 and strips it off, thus forcing it rapidly upward and opening quickly the switch, to which the core 53 is connected.

51. The core 53 is connected by a pivot link 55 with the upper end of a lever 56 which is pivotally mounted in the body 57 which has the binding post 58, the switch 20 and the lever 56. The upper end of the lever 56 and the upper

end of the lever 50 is connected by the contact 59 which has the binding post 64, or a dash pot 65. 52. Lever 56 is supported from the lever 50 and the adjacent end of the lever 50 is connected by an impacting link 66 with a connecting rod 67, which is pivotally mounted in a link 68 with lever 50, pivoting on the piston 70 which corresponds with the dash pot 65. 53. A check arm 71 consisting of a bell 72 adapted to rotate with the lever 50, over 73 of the piston, pivoted in the piston through the piston arm 74 to readily prevent descent of the piston. 54. Lever 56 is caused to move slowly upward by the lever 50 and gives the opportunity to move the lever 56 and piston 70 in the direction of the piston 70, so that the piston 70 may be threaded through the piston 70 and connected with the lever 59, so that the piston 70 may regulate the descent of the piston 70 may be threaded through the piston 70 and thus the set screw 75 may be taken out for a length of time so that the dash pot 65 may be removed, and consequently it is necessary to open the circuit 76 so that the circuit 76 may be closed through the dash pot 65 when the dash pot 65 is closed. 55. The binding post 64, or a dash pot 65, is connected to the binding post 77, or a dash pot 78, and the binding post 77, or a dash pot 78, is connected to the binding post 79, which is connected by the wire 80 with the lever 56, and the binding post 81, or a dash pot 82, which is connected by the wire 83 with the lower end of the coil of the solenoid 52, or a dash pot 82, the upper end of said coil is connected by the wire 84 with the binding post 81, or a dash pot 82, while the circuit is closed. 56. The solenoids 52, or a dash pot 82, the solenoid 52 will be deenergized, while the solenoid 52 is energized, the circuit is, that case being connected through the wire 84, binding post 81, or a dash pot 82, binding post 83, or a dash pot 84, contact 85, binding post 86, wire 87 and binding post 88, or a dash pot 89.

57. The operation of the device as a two circuit device will now be readily understood. Assuming that the switch blades 21 and 22 have just been caused to close the circuit between the switch 20 and 21, as soon as this occurs the solenoid 52 is energized and the core 53 is raised very slowly owing to the resistance of the dash pot 65 until it reaches the extreme top, when the core 53 is deformed, and causes the piston 70 into the dash pot 65, or a dash pot 65, the piston 70 being caused to move upward by the lever 56, or a dash pot 65, the switch 20 will be

draws the core 42 upward rapidly as the valve 51 is then opened and the arms 45 and 46 ultimately engage the surfaces 49 and 50 opening the circuit between contacts 20 and 21 and simultaneously closing it between the contacts 26 and 27. This shifts the work circuit which had been through the lights 16 to the lights 17 and at the end of the upward movement of the plunger 42 it strikes 10 the auxiliary plunger 56 and opens the switch at contacts 62 and 63 quickly, thus de-energizing the solenoid 40 and allowing the core 42 to fall slowly, as described, until the contracted portion of the dash pot 44 is 15 passed, after which it will fall rapidly and in its final movement, open the contacts 26 and 27 by the engagement of the arms 45 and 46 with the arms 47 and 48. This completes the cycle of operations described, 20 which will thus be repeated indefinitely so long as the apparatus is in circuit, and consequently the two sets of lamps 16 and 17 will be alternately illuminated for the desired intervals. Where the plunger is em- 25 ployed simply to control one circuit, as indicated in Fig. 5, the lower contacts 26 and 27 may be omitted and in that case, the connections would be as shown in Fig. 5.

I claim—

30 1. In an automatic electric switch, the combination with a work circuit, of a shunt circuit, a solenoid magnet in the said shunt circuit, a second shunt circuit, a switch in said second shunt circuit operated by the core of the magnet in the first shunt circuit, a solenoid magnet in the second shunt circuit with its core in axial alinement with the core of the first magnet, a member adjustably threaded into one of said cores so 35 that the time of the striking of the core of the magnet in the first shunt circuit by the core of the magnet in the second shunt circuit to open the switch in the second shunt circuit can be regulated, and mechanism 40 for regulating the rate of separation of said cores.

2. In an automatic electric switch, the combination with a work circuit, of a shunt circuit, a solenoid magnet in said shunt circuit, a second shunt circuit, a switch in said second shunt circuit operated by the core of the magnet in the first shunt circuit, a solenoid magnet in the second shunt circuit in axial alinement with the magnet in 45 the first shunt circuit, a switch in the first shunt circuit operated by the magnet in the second shunt circuit, a supplementary core

for the magnet in the second shunt circuit carried by and forming a physical extension of the core of the magnet in the first shunt circuit, and means for adjusting the position of the supplementary core, the main core of the solenoid magnet in the second shunt circuit being adapted to engage its supplementary core to open the switch in 60 said second shunt circuit positively.

3. In an automatic electric switch, the combination with a work circuit, of a shunt circuit, a magnet in said shunt circuit, a second shunt circuit, a switch in the second shunt circuit operated by the magnet in the first shunt circuit, a magnet in the second shunt circuit, and a swinging switch in said first shunt circuit provided with two engaging surfaces, and means for causing the magnet in the second shunt circuit to act when energized to first open the switch in 70 said first shunt circuit by engagement of its armature with one of the surfaces and then to open the switch in the second shunt circuit 75 and finally to close the switch in the first shunt circuit by its armature engaging the second surface on its return movement.

4. In an automatic electric switch, the combination with a work circuit, of a shunt circuit, a magnet in said shunt circuit, a second shunt circuit, a switch in said second shunt circuit operated by the magnet in the first shunt circuit provided with an armature, a magnet in the second shunt circuit, 80 a swinging switch in the first shunt circuit provided with two engaging surfaces, and means for causing the magnet in the second shunt circuit to act when energized to first open the switch in the first shunt circuit by 85 the engagement of its armature with one of the surfaces and then to open the switch in the second shunt circuit, and finally to close the switch in the first shunt circuit by its armature engaging the second surface on its 90 return movement, and a dash pot connected to the armature of the magnet in the second shunt circuit and having a resistance release operating during the engagement of the armature of the second surface to close 100 the switch automatically.

In witness whereof, I have hereunto set my hand and affixed my seal, this 27th day of April, A. D. 1911.

GEORGE F. KIRCHHOFF.
